MECHANISM FOR CONSTRUCTING CONCRETE PIPE

Filed May 17, 1930

Fig. 3.

By A. W. Schultz,
G. Kennedy, Attorney

UNITED STATES PATENT OFFICE

ALFRED W. SCHULTZ, OF WATERLOO, IOWA

MECHANISM FOR CONSTRUCTING CONCRETE PIPE

Application filed May 17, 1930. Serial No. 453,226.

My invention relates to improvements in producing cement or concrete pipe, and the object of my improvements is to supply mechanism therefor adapted, during the process 5 of shaping a hollow tile or pipe section, to differentially consolidate, and strengthen one part of the section, such as a bell-end of a pipe section, and to perform said functions in a certain relation and succession automatically.

An object of said improvements is to also provide effective means for vibrating the supports for the bell-end of a mold casing and the latter evenly, rapidly and with short 15 travel agitation, whereby the concrete contents of the bell-end of the mold casing before the forming of the main body of the tile are alone agitated in a manner necessary for consolidating the diverse components of such 20 concrete to consolidate the bell-end of a tile to strengthen it against all stresses of use and emplacement.

Another object of my improvements is to combine with the vibrator means for lifting 25 it to and from its operating position, and other means for actuating the vibrator, whereby both devices may be operated by valve-controlled connections to a source of pneumatic pressure, and in a determined succession, automatically.

Another object of my improvements is to include in the train of vibrating elements, a plurality of spring-supported tappets mounted for radial adjustments relative to a center 35 of the means supporting the tappets, whereby the machine may be adjusted for vibratory action on tile-casing or pallets and tiles of differing diameters.

All of these objects have been successfully 40 attained in reduction to practice, by the mechanisms which are hereinafter described and claimed, and which are illustrated in the accompanying drawing, in which Fig. 1 is a front elevation of my machine, with parts 45 in section or broken away, and Fig. 2 is a top

plan of the vibrating table or plate with tappets adjustably mounted thereon. Fig. 3 is an enlarged sectional view of the vibrator and associated elements in detail, with parts in elevation or broken away.

My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

My improved machine has a solid base 2 upon which is rigidly supported a metal skeleton frame 1, above and around a pit 23. Sockets 4 are fixed on the front side beams of the frame 1 to project towards each other on the same level and receive and step fixedly the lower ends of slideway rods 5. The upper ends of said rods are likewise fixed in other sockets, which project outwardly, however, from a cross-beam 3 having a medial apertured bearing 17 seating a rotatable and also reciprocable shaft 15, upon whose upper end is secured a belt-carrying pulley 16 driven by mechanism not detailed herein. The wheel 75

16 is splined on said shaft non-rotatably but to permit the reciprocatory movements of the shaft therethrough. Side-rods 11 have their lower ends stepped fixedly in outwardly directed apertured lugs 9 on apertured bearing terminations of an upwardly ledged circular or annular top platen 6 concentric with the shaft 15, said bearing terminations being slidably mounted on the fixed side-rods 5. A cross-beam 7 has a medial apertured bearing 18 fixed on the shaft 15 above the platen 6. The upper ends of the outer side-rods 11 are slidably seated in apertured ears 12 on the outer terminations of the top cross-beam 3. Sheaves are rotatably mounted in the top of 80 85 90

the frame 1 in front at opposite sides of the wheel 16, and reeved thereupon are the depending cables which are connected to the end parts of the cross-beam 7, and whereby the 5 shaft 15 is lifted or lowered by mechanism not shown. Included in one of the frame supports in front is a rotary table 19 having a plurality of apertured seats for bottom supporting rings for an annular bottom pallet 10 44, upon which the lower end 47 of the bell-end mold casing 46 is removably mounted, concentric with the shaft 15.

The annular top platen or pallet 6 receives concrete materials from an inclined spout or 15 chute 14 as supplied by an endless conveyer not shown, these materials dropping into the interior of the mold casing 46 at the proper times. A former-head 48 of cylindrical shape and fixed on the lower termination 20 of the shaft 15 may move into or out of the mold casing 46 as the shaft is alternately lowered or lifted, and the former-head carries removable troweling members 49 of a well-known type.

25 Spaced below the annular pallet 45, and concentric with the shaft 15 above is a circular plate 37 having a bottom central convex boss 38 for a purpose to be described supported for limited free tilting on the center of the discoidal top member of a pneumatic vibrator 30, the latter resting upon a circular table 29 terminating the upper part of a plunger-stem 28 which moves into a cylinder 20 supported upon the floor of the pit 23. 30 The vibrator 30 may be of any desired description suitable for pneumatic actuation, wherein compressed air introduced into its passages sets up a short travel quick vibration which is communicated to the plate 37 by way of its boss 38. The vibrator has a discharge tube 32 to the atmosphere, and its interior passages communicate with a supply pipe 31 containing a valve-chamber 33 with a valve having an outer operating arm 35, 35 the pipe having thereabove a connection 34 with a supply of air under pressure.

The cylinder 20 contains an imperforate piston on the stem 28, and at top and bottom ports communicating respectively with pipes 21 and 22 to supply and exhaust air alternately from opposite ends of the cylinder, the pipes including a valve-chamber 24 having an operating outer arm 27, and a supply connection 26 with said source of compressed air. An adjustable sleeve 10 is mounted on one of the side-rods 11 intermediate the operating arms 27 and 35, to act as an engaging tripping member for the arm 27.

40 The circular plate 37 has radial rows of holes 43 to receive the lower ends of removable pins or tappets 42, the pins or tappets having near their lower ends annular flanges to seat them upon the plate. Near said rows of holes are other holes to receive bolts 39 45 whose lower ends traverse also alined holes

in the annularly flanged top 50 of the vibrator 30, secured by nuts 41, and coiled compression springs 40 are mounted on the bolts between said nuts and said annular top to steady the plate 37. The upper ends of the tappets 42 contact with the under face of the pallet 44 at equal distances apart and from the center of the plate 37. When a pallet 44 of larger diameter is used upon which to mount a larger mold casing 46, the tappets 75 may be seated in holes 43 of the plate 37 farther from its center, adjustably.

The mold casing 46 is shown in Fig. 1 seated clampingly between the upper platen 6 and the lower pallet 44, with the shaft 15 lowered to place the former-head 48 in its lowermost position in the mold casing concentrically, and the shaft being put into rotation, concrete materials are dumped from the trough 14 upon the platen 6 and to drop into the mold casing bell end 47, where the former-head forms an interior wall and the interspace fills with the concrete material. The shaft 15 is then placed in rotation, so that the former-head with its trowels 49 90 shape and trowel the concrete in the bell end 47. At this moment mechanism not shown draws upwardly the cables connected to the cross-head member 7 moving it and the shaft 15 upwardly as the shaft is still rotating.

95 During this momentary troweling of the bell end of the tile while the right-hand side rod 11 is lowered to depress the operating arm 35 of the lower valve-chamber 33, the chamber is open allowing compressed air to 100 pass through the pipe 21 and the passages of the vibrator 30, causing a very rapid mechanical vibration if it, which is communicated to the plate 37 by way of its depending spheric central boss 38, and by way of the 105 tappets 42 to the pallet 44 to jar the contents of the bell end of the mold casing, causing the materials to segregate into a state where the lower part of the bell end of the casing receives the finer cement settling.

110 The cement content becomes more compact and harder when dried, so that in the bell end of the formed tile, it strengthens the part most likely to be broken by handling or transportation. As the shaft then ascends while 115 rotating to shape the body of the tile cylindrically above its bell end, the side rod 11 is drawn up releasing the valve arm 35, so that the stretched spring 36 connected to its opposite part reacts causing the closing of 120 the chamber, and hence stopping the action of the vibrator 30, so that the body of the tile is not in any way vibrated or jarred during its formation in the mold casing. The lug 10 on the rod 11 then lifts the platen 6 125 by engaging its adjacent end member lug 9, releasing the top of the mold casing as the former-head 48 leaves it in its upward progress with the shaft 15.

130 As the arm 27 of the upper valve-chamber

24 has during this operation been held in depression by engagement with the end part of the cross-beam 18, as the latter lifts with the shaft, the arm is rocked by draft of a 5 acting spring in like manner to the other, reversing the air current, so that the plunger in the cylinder 20 is driven reversely, lowering the vibrator 30 together with the superimposed plate 37 and its tappets 42, to clear 10 the pallet 44, whereupon the rotatable table 19 may be rotated to displace the mold casing and formed tile therein to a place where it may be removed from the table, and permitting another mold casing on the table to be 15 rotated therewith into place. The actuations of the two-valve chambers are thus made automatic, permitting operation of the vibrator 30 at the right time, and the raising and the lowering of the vibrator before and after 20 its intermediate actuation.

Having described my invention, what I claim as new, and desire to secure by Letters Patent, is:

1. In apparatus of the character described, 25 a pallet, tappets contacting with outer parts of the pallet therearound, a plate having circumferentially equidistant radial rams of sockets seating said tappets removably and for radially adjustably seating thereof, a vi- 30 brator centrally and resiliently supporting said plate to steady the plate while agitating it, and a device adapted to shift the said devices into and out of operating relation with the pallet.

35 2. In apparatus of the character described, a pallet, a plate spaced beneath said pallet, tappets removably mounted on and around said plate abutting the under face of the pallet concentrically, a vibrator below and cen- 40 trally supporting said plate, resilient connections between said vibrator and plate therearound to steady the plate, a pneumati- cally actuated elevator supporting said vi- 45 brator to lift and lower it, valve-controlled means for automatically charging and ex- hausting said elevator, valve-controlled means for automatically supplying and ex- hausting a fluid under pressure to and from said vibrator, and intermediate automatical- 50 ly coacting means for alternating the opera- tions of said valve-controlled means.

3. In apparatus of the character described, 55 a pallet, a plate below said pallet with a cen- tral depending boss of convex shape, tappets mounted on said plate for impinging upon the pallet to vibrate it, the plate having a plurality of radially disposed apertures in which the tappets are seated for removable adjustments therein on the plate, means for 60 vibrating the plate by contact only with its central boss, and means for shifting said devices into and out of tamping action on the pallet.

4. In apparatus of the character described, 65 a pallet, a plate spaced below the pallet, tap-

pets seated removably around the plate to at times vibrantly engage and vibrate the pallet, a vibrator below and adapted to centrally engage the plate, resilient means positioned to engage and steady the plate, a pneumatically actuated apparatus for shifting said devices into and out of vibrating operating action upon the pallet, and means for periodically actuating the vibrator and the lifting apparatus alternately and automatically.

In testimony whereof I affix my signature.
ALFRED W. SCHULTZ.
